(57) **CLAIM**

The ornamental design for a controller cradle, as shown and described.

DESCRIPTION

FIG. 1 is a right-side, back, and top isometric view of a controller cradle, showing the new design.

FIG. 2 is another right-side, back, and top isometric view of the controller cradle.

FIG. 3 is a top plan view of the controller cradle.

FIG. 4 is a right-side elevation of the controller cradle, the left side being a mirror image thereof.

FIG. 5 is a front elevation of the controller cradle.

FIG. 6 is a rear elevation of the controller cradle; and,

FIG. 7 is a bottom plan view of the controller cradle.
